A. SUNDH.

FLUID MOTOR OR PUMP.

APPLICATION FILED, APR. 24, 1914.

Patented Nov. 9, 1915.

UNITED STATES PATENT OFFICE.

AUGUST SUNDH, OF HASTINGS-UPON-HUDSON, NEW YORK, ASSIGNOR TO OTIS
ELEVATOR COMPANY, A CORPORATION OF NEW JERSEY.

FLUID-MOTOR OR PUMP.

1,159,613.

Specification of Letters Patent.

Patented Nov. 9, 1915.

Application filed April 24, 1914. Serial No. 834,033.

To all whom it may concern:

Be it known that I, AUGUST SUNDH, a citizen of the United States, residing in Hastings-upon-Hudson, in the county of 5 Westchester and State of New York, have invented a new and useful Improvement in Fluid-Motors or Pumps, of which the following is a specification.

My invention relates to fluid motors or 10 pumps and is particularly directed to a motor or pump comprising a plurality of oscillating cylinders which are radially disposed about a common crank shaft such as is disclosed in my copending application for patent, Serial No. 826,168, fluid motors or 15 pumps.

One object of the invention is the provision of means for effecting a balance against the action of fluid pressure on the cylinders.

Another object of the invention is the provision of improved means for supporting the oscillating cylinders so as to obviate friction. 20

Another object of the invention is the provision of means for compensating for all 25 bending and other strains which may develop through wear, imperfect alinement of parts or other causes.

A further object of the invention is the provision of a novel arrangement of ports 30 and fluid passages whereby fluid may be directed to and from the working cylinders in a manner conducive to high speeds and efficiency.

Other objects of the invention will appear 35 hereinafter, the novel combinations of elements being pointed out hereinafter.

In the drawings, Figure 1 represents in 40 front sectional elevation, a fluid motor or pump containing an embodiment of my invention; Fig. 2 is a side sectional view taken on the line 2, 2, of Fig. 1; Fig. 3 is a fragmental side sectional view taken on the line 3, 3, of Fig. 1.

Like reference numbers denote like or 45 similar parts in all of the figures.

Referring to the drawings, the pump or fluid motor comprises a vertical casting 1, which is carried upon a substantial bed 2. This casting contains a plurality of symmetrically arranged circular bores each of 50 which is lined by a bushing such as 3 and 4, within which are located the oscillating disks such as 5 and 6, respectively. The

disks are bored out at right angles to their axes so as to form cylinders and within each 55 cylinder is a single acting trunk piston such as 7 and 8. The pistons are all connected to a common crank pin 9 carried by the overhanging counterbalanced crank shaft 10. The latter is carried in roller bearings 11 located in the head 12 which is supported upon the cover plate 13 secured to the casting 1.

Since the cylinders, pistons and associated parts are similar to each other, respectively, a detail description of one will answer for 65 all. Take for example the cylinder shown at the top of the pump. The disk 5 in which this cylinder is formed is supported upon trunnions 14, 14, which turn in anti-friction bearings supported by the cover plate 13 70 and pump casting 1, respectively. A wide annular groove 15 is cut in each lateral face of the cylinder disk 5, and these grooves are connected by ports or ducts 16 so as to equalize the fluid pressure on opposite sides 75 of the disk in case there should be a leakage into one or both of the grooves. By reason of this construction, each of the cylinder disks is perfectly balanced against lateral fluid pressure, and the cylinder disks will 80 oscillate freely in the trunnion bearings without end thrust and side friction so that it becomes a simple matter automatically to lubricate the disks.

The piston 7 is hollowed out so as to reduce its weight, and the top of the piston is slotted as shown so as to permit the same to extend substantially to the end of the cylinder bore on its inward stroke without in any way restricting the passage of fluid to and 90 from the cylinder. This arrangement permits of an unusually long piston and a correspondingly long bearing for the same in the cylinder bore, which makes for durability and overcomes the tendency for the cylinder bores to wear oval after long continued service.

The crank pin end of the piston is pivotally connected to a block 17 by means of a pin 18 and this block, as well as the corresponding blocks of the other pistons is maintained in contact with the crank pin 9 by means of a ring 19 and flanged cap 20, an anti-friction roller bearing being interposed as shown. This pivotal connection between 100 the pistons and the crank pin is a feature

of great practical value. For example, in the construction of any reciprocating pump or motor, it is almost a mechanical impossibility to arrange the axis of each cylinder bore at an exact right angle to the axis of the crank shaft, and even though it were possible, the slightest wear of the crank shaft or crank pin bearings would tend to destroy this exact alignment. Furthermore, unless the crank shaft be made unreasonably large in diameter, there is sure to be a slight spring in the same under load. This being so, it follows of necessity that the pistons would be cramped in the cylinders, or the cylinders themselves, would be cramped and the resultant twisting strain on the parts would be enormous. By reason of the pivotal connection which I have provided, the axis of a piston may not necessarily be in perfect alignment with the crank shaft and yet the pistons may operate with perfect freedom from strains and cramping action due to the above noted or other causes. In this manner the cylinder disks may rock on their respective trunnions with practically no friction and no appreciable strain will be placed upon the trunnion bearings regardless of the pressure of the working fluid and regardless as well to leakage or imperfect alignment of parts.

An important feature of my invention, which as yet has not been described, consists in the arrangement of fluid ports and passages. Take for example one of the lower cylinder disks 33. In this disk there are two ports such as 27 and 28, which are arranged on diametrically opposite sides of the periphery of the disk and each of these ports is connected to the cylinder bore by a corresponding port or passage 25 and 26, respectively. The port 27 is adapted alternately to register with the fixed ports 31 and 32, while the cylinder port 28 in like manner is adapted alternately to register with the fixed ports 29 and 30. Between adjacent cylinders are arranged four chambers such as 21, 22, 23 and 24, which are cored in the casting 1 and these chambers are in communication with the ports 30, 29, 31 and 32, respectively. The right hand head or cover plate 34 (see Fig. 2) is provided with two annular chambers 35 and 36 which are permanently connected by the pipes 37 and 38 to any suitable exhaust and pressure supply, respectively. The exhaust chamber 35 is in constant communication with the chambers 22 and 24, while the pressure chamber 36 is in communication with the chambers 21 and 23, and this same arrangement is carried out with respect to all of the other corresponding chambers in each group of chambers intermediate the cylinders.

The operation of the device as a fluid motor is as follows: Fluid under pressure enters the annular chamber 36 by way of the

pipe 38 and passes into all of the chambers 21 and 23. The cylinder disk 33 at the present time is in such position that its port 27 is open to the chamber 23, while the opposite cylinder port 28 is open to the chamber 21. Now, since both of these chambers 21 and 23 are connected to the pressure supply, fluid enters the cylinder bore of the disk 33 from diametrically opposite sides of the disk and the piston is forced outwardly and the crank shaft is rotated in a left hand or counterclockwise direction. As soon as this piston reaches the end of its stroke, the ports 27 and 28 are cut off from the ports 31 and 30, respectively, and then moved into register with the ports 32 and 29, respectively. These latter ports are connected to the chambers 24 and 22, respectively, both of which are in communication with the annular chamber 35, which is connected to the exhaust pipe 37. The cylinder 33 therefore is open to the exhaust and a further rotation of the crank shaft drives the piston downward and the fluid in the cylinder is forced out. As the crank shaft continues to rotate, the cylinder disk 33 is oscillated back and forth and the cylinder is alternately connected to the pressure and exhaust.

The operation of the other cylinders is exactly like the one just described, and since the present embodiment of my invention contains five cylinders, the cycle of operation of one cylinder is just 72° removed from that of an adjacent cylinder, hence but a single piston can be at its dead center at one time, and the torque will be substantially constant throughout the entire crank circle.

By reason of the novel arrangement of ports and fluid passages, it is readily seen that whatever pressure may be directed to one side of the periphery of a cylinder disk, an equal and opposite pressure will be directed to the opposite side or periphery of the disk, and hence each cylinder disk will at all times be absolutely balanced against fluid pressure and all friction due to an unbalanced condition is absolutely done away with.

Furthermore, since fluid is enabled to flow to and from the cylinders by a double set of ports, the velocity of fluid flow through the ports will be substantially one half of that found in other pumps or fluid motors of a similar type. By reason of this fact alone, not only is the efficiency of the device very high, but also its possibilities of unusually high speed and power output.

While my invention as disclosed comprises a pump or motor of five cylinders, the same may be made with but one cylinder or any desired number of cylinders. The device when used in the capacity of a motor, may be operated in either direction of rotation, and when used as a pump the direction

of fluid flow may be in either direction. The fluid used in the device may be water, oil steam or other fluid or liquid, and if so desired, the cylinders may, by obvious changes, be constructed so as to be double acting.

5 What I claim is:—

1. A fluid motor or pump comprising a plurality of oscillating disks, cylinders formed in said disks, means for effecting a fluid balance on the lateral faces of said disks, and anti-friction bearings in which 10 said disks oscillate.

2. A fluid motor or pump comprising a plurality of oscillating disks, cylinders formed in said disks, means for effecting a fluid balance on the lateral faces of said disks, trunnions on the disks, and anti-friction 15 bearings for the trunnions.

3. A fluid motor or pump comprising a plurality of oscillating disks, cylinders formed in the disks, means for balancing said disks against fluid pressure, and trunnions upon which said disks oscillate.

4. A fluid motor or pump comprising a 25 disk, a cylinder formed in said disk, a casing in which said disk is adapted to oscillate, anti-friction bearings carried by the casing and supporting the disk, and fluid means for balancing said disk against end 30 pressure whereby the disk will assume a central position in said casing.

5. A fluid motor or pump comprising a plurality of oscillating disks, cylinders formed in the disks, a casing surrounding 25 each disk, a pivotal support for each disk in its respective casing, and fluid means for maintaining the disks in a central position with respect to their respective casings whereby equalized fluid pressure may lubricate 40 the surfaces of the disks.

6. A fluid motor or pump comprising a substantially circular casing, a plurality of circular bores radially disposed about the center of the casing, oscillating disks in the 45 circular bores, cylinders formed in the disks, pressure ports arranged in the circular bores on diametrically opposite sides of each disk, exhaust ports arranged in the circular bores on diametrically opposite sides of each disk, 50 and ports in the disks communicating with the cylinder bore therein adapted to register first with both pressure ports and then with both exhaust ports as the disk is oscillated, whereby a fluid balance is effected 55 upon diametrically opposite sides of the disks.

7. A fluid motor or pump comprising a substantially circular casing, a plurality of circular bores radially disposed about the 60 center of the casing, oscillating disks in the circular bores, cylinders formed in the disks, two sets of ports arranged in each circular bore on opposite sides of each disk, ports in the periphery of each disk communicating 65 with the cylinder bore therein and arranged

diametrically opposite each other, and means controlled by the oscillation of the disks for effecting a register of the ports in the disk first with one set of ports in the circular bore and then with the other set of 70 ports in the circular bore so that fluid may enter or discharge from a cylinder simultaneously on diametrically opposite sides of the periphery of the disks and thereby effect 75 a fluid balance of the disks.

8. A fluid motor or pump comprising a substantially circular casing, a plurality of circular bores in the casing, disks adapted to oscillate in the circular bores, a cylinder formed in each disk, ports arranged on diametrically opposite sides of the periphery of each disk and communicating with the cylinder therein, and ports in said circular bores adapted alternately to register with the said disk ports so that fluid may enter or 80 discharge from said cylinder bores simultaneously from both peripheral ports in the disks.

9. A fluid motor or pump comprising a substantially circular casing, a plurality of 90 circular bores in the casing, disks adapted to oscillate in the circular bores, a cylinder formed in each disk, ports arranged on diametrically opposite sides of the periphery of each disk and communicating with the cylinder therein, a double set of ports in each circular bore adapted alternately to register with the disk ports as the disks are oscillated, a chamber common to one set of ports and an independent chamber common 100 to the other set of ports, one of said chambers being adapted to receive the fluid discharged from the cylinders and the other supplying the cylinders with fluid.

10. A fluid motor or pump comprising a 105 substantially circular casing, a plurality of circular bores in the casing radially disposed about the center thereof, disks adapted to oscillate in the circular bores, a cylinder formed in each disk, a plurality of chambers located in the casing between each circular bore, ports leading from said chambers to the periphery of each disk, ports in the disks communicating with the cylinder bore therein and adapted to register with 110 the ports leading from the chambers, and independent fluid supply and exhaust chambers adapted to connect the chambers in the casing in groups whereby fluid may enter any one of said cylinders simultaneously on 115 opposite sides of the periphery of the cylinder disk.

11. A fluid motor or pump comprising a substantially circular casing, a plurality of circular bores in the casing radially disposed about the center thereof, disks adapted to oscillate in the circular bores, a cylinder formed in each disk, a plurality of 125 chambers located in the casing between each circular bore, ports leading from said chambers 130

bers to the periphery of each disk, ports in the disks communicating with the cylinder bore therein and adapted to register with the ports leading from the chambers, a removable cover member containing independent fluid supply and exhaust chambers secured to the said casing, and ports leading from the chambers in said cover member to the chambers in the casing whereby the latter chambers are connected in groups so that fluid may be directed simultaneously to or from both of said disk ports in any one of the disks.

12. A fluid motor or pump comprising a plurality of rocking disks radially disposed about a common center, cylinders formed in said disks, pistons in the cylinders, a crank shaft common to all of the pistons, and a connection between each piston and the crank shaft comprising a connecting rod hinged intermediate its ends.

13. A fluid motor or pump comprising a plurality of rocking disks radially disposed about a common center, cylinders formed in said disks, pistons in the cylinders, a crank shaft common to all of the pistons, and means comprising a two part hinged connecting rod for preventing bending and

twisting strains from being transmitted from the crank shaft to the pistons.

30

14. A fluid motor or pump comprising a plurality of oscillating cylinders radially disposed about a common crank shaft, trunnions on which said cylinders oscillate, a trunk piston in each cylinder, a connection between each piston and the said crank shaft, said connection being arranged to yield at a point intermediate its ends.

15. A fluid motor or pump comprising a housing or casing, a plurality of oscillating disks in said casing radially disposed about a common crank shaft, a cylinder bore in each disk, a plunger in each cylinder connected to the crank shaft, fluid means for equalizing the pressure on said disks, and a yielding connection between each piston and the crank shaft for preventing the latter from exerting a side pressure on the said disks.

In testimony whereof, I have signed my name to this specification in the presence of two subscribing witnesses.
